NIELS P. NIELSEN, OF CUSTER, WASHINGTON

HENHOUSE DROPPING BOARD CLEANER

Application filed March 30, 1929. Serial No. 351,167.

My invention relates to improvements in hen-house dropping boards, more especially those wherein long dropping boards may be cleaned quickly of an accumulation of droppings thereon by a single operative and has for an object to provide means whereby a relatively small movement of a long dropping board is sufficient to clean the entire length thereof.

Another object of my improvement is to provide means for the automatic removal of the droppings from said board coincident with said cleaning movement thereof.

Another object of my improvement is to provide for the storage of said removed droppings, nonaccessible to the hens, for farther removal at a later and convenient time.

Another object of my improvement is to provide for the cleaning and return movements of said board to be made by the reverse operations of simple mechanism within the power of a single operative.

Another object of my improvement is to provide mechanism suitable to cause said return movements of said board to also serve to clean the same.

Another object of my improvement is to subdivide said long dropping boards into short units easily assembled and taken apart and convenient for storage out of operative position.

Another object of my improvement is to provide simple, durable, easily operable and not expensive mechanism for the above-stated objects.

Other objects of my improvement will appear as the description proceeds.

I attain these and other objects of my improvement with the mechanism illustrated in the two sheets of accompanying drawings, which form a part of this application, in which Figure 1 is a front elevation of my dropping board with the mechanism for operating the same in place thereon shown in operative position in a hen house the related portion of the floor and end and partition walls of which are shown in section and the supporting frame work of which is broken away above the roosting poles, Fig. 2 is the

same as Fig. 1 with the dropping board units shown in the positions attained when at the end of the said cleaning movement thereof, Fig. 3 is a top plan view of Fig. 1, Fig. 4 is a segregated bottom plan view of one of the scrapers, Fig. 5 is a bottom plan view of the driving unit of the dropping board and Fig. 6 is a cross section elevation of Fig. 2 taken on the line 6—6 thereof drawn on a larger scale.

Similar characters refer to similar parts throughout. Certain parts are broken away for lack of space or to show other parts hidden thereby.

With more particular reference to the designated parts: My dropping board is preferably located directly in front of the rear wall of the hen house of which 7 is the floor, 8 an end wall and 9 the rear wall, while 10 is a partition wall. Two parallel track stringers in a horizontal plane are fastened to supporting frame work near and parallel with rear wall 9 and extend from end wall 8 through partition 10. Tracks 12, 12 are fastened on top of stringers 11. Stops 13 and 14 are at the right-hand and left-hand ends of stringers 11 and project above the level of the same. Roosting poles 15 are above stringers 11 and are supported on rails fastened to the rear wall and to uprights 16. Said uprights are fastened to the front of front stringer 11 with intervening blocks.

Dropping board units 17, a17 and 18 are shown. Unit 17 consists of a flat floor, with chamfered ends b17, fastened to end beams 19, 19 and side beams 20, 20 beneath. Unit a17 consists of floor a17 with chamfered ends c17 fastened to end beams 19, 19 and side beams 20, 20 below. Driving floor unit 18 consists of a flat floor with one chamfered end d17 fastened to end beams 21, 21 and side beams 22, 22 beneath. Longitudinal bottom board 23 is fastened beneath end beams 21 of unit 18.

Each of said dropping board units has ball-bearing wheels 24 mounted for revolution in its side beams which are disposed to roll on tracks 12, 12 when said side beams are disposed between front guides 25 and rear guide 26. For the said rear guide see Fig. 6.

Three bolts 27 are extended through aligned holes in said adjacent end beams to fasten said units together and are long enough to allow said units to be separated by 5 intervening spaces 43, 43 as shown in Fig. 2. Said bolts are free in said holes and allow the adjacent ends of the floors of said units to bear against each other as shown in Figs. 1 and 3. Preferably the middle one of each 10 set of said bolts is adjusted to determine the width of opening or space 43 and the other two bolts of each set are adjusted to serve as auxiliaries to said central bolts.

Shaft 29 is mounted for revolution in bearings 15 in stringers 11 beneath the ends of driving unit 18 when it occupies its operative position shown in Fig. 1 and also when it is in its cleaning extreme position shown in Fig. 2. Driven sprocket wheel 28 is fastened on the outer end of shaft 29 to revolve therewith. Shaft 31 is mounted for revolution in bearing 32 fastened beneath front stringer 11, see Fig. 2, and has fastened thereto driving sprocket wheel 30 in chain 20 relation with said sprocket 28 and over said sprockets is placed and engaged sprocket chain 33. Handle crank 34 is fastened on the outer end of shaft 31 and used to turn sprocket 30 which has more teeth than 25 sprocket 28 thus providing a turning advantage to the hand applied to said handle.

Sprocket chain 35 is fastened longitudinally of driving unit 18 beneath bottom board 23 thereunder and its ends are secured by engagement with one of central bolts 27, in one 30 of cross beams 21, and with bolt 36 in the other of said cross beams 21. Sprocket wheel $a28$ is fastened on shaft 29 to engage chain 35. Chain 35 is in this case used for the purpose of a rack and in practice is found to serve very well.

The construction is such that by revolving crank handle 34 backward driving unit 18 is moved from its position of operation 40 shown in Fig. 1 to its cleaned position shown in Fig. 2. Then by revolving said handle crank in a forward direction said driving unit is returned to its position shown in Fig. 1.

Scraper bars 37 have notched ends to engage with hooks 39 fastened to uprights 16 and in notched blocks $a39$ fastened on the rear house wall. Said bars have areas 38, 38 on each end thereof to bear on said hooks and blocks. See Fig. 4.

55 A scraper blade 40 is fastened to each of bars 37 with bolts 42 extended through holes in said bar and slots 41 in said blade. See Fig. 6. Said slots provide means of adjusting the position of said blade on the bar.

60 When the dropping board was driven to its operative position shown in Fig. 1 by turning crank 34 forward the adjacent ends of the units thereof were caused to abut and bear against each other to occupy the operative 65 position shown in Fig. 1 and provide a con-

tinuous plane from end to end to hold whatever droppings may be deposited thereon. But on returning said dropping board to its cleaned position shown in Fig. 2 bolts 27 allow the units to separate and provide spaces 70 43 therebetween as referred to. Scraper blades 40 are so disposed that one of each is pendent centrally over each of the two spaces 43 and one over and to the rear of the rear end of unit 17. Also said scraper blades are 75 adjusted vertically to bear on the dropping board as it passes beneath and to follow chamfered ends $b17$, $c17$ and $d17$ downward to a short distance only and not catch to engage with the passing ends of said units. 80

Holders 44 are fastened to the frame work below stringers 11 vertically beneath scraper blades 40 and preferably incline downward from their front ends rearward to pass through openings in near wall 9 and have their open lower ends protruding through said wall at $a44$. The said openings in the rear wall are closable by doors 45. Holders 44 are designed to receive the droppings scraped from the passing dropping board 85 units by blades 40 which fall through spaces 43 and over the rear end of unit 17. The front ends of the holders extend beyond the front edge of the dropping board as shown and are preferably closed to prevent 90 the entry of hens. Yet there is sufficient opening forward of the dropping board to allow disinfectants to be introduced into the holder if desired. Any accumulation of droppings in holders 44 may be removed by using a suitable hoe operated through opened door 45 and deposited in a receptacle, such as a wheel barrow, placed beneath open outer end 95 $a44$ for that purpose.

The functions of the several related parts 105 of my dropping board have been explained during the particular description thereof and little need be added to fully disclose the way in which it is cleaned of droppings.

Starting with the several units of the board 110 in their relative positions shown in Fig. 1, it is assumed that their surfaces contain a litter of droppings. Handle 34 is grasped and turned backward which moves driving unit 18 leftward till it bears against stop 14 115 and also moves units $a17$ and 17 in the same direction thus causing spaces 43 between them. The board now occupies the position shown in Fig. 2. During the leftward movement of the units their top surfaces pass beneath scraper blades 40 which bear thereon and collect said droppings and retain the same till said openings 43 occur beneath the two left-hand blades and the rear end of unit 17 has passed beyond the right-hand 120 blade. The droppings held back by said scrapers fall through said spaces 43 and over the rear end of unit 17 down into holders 44. Usually the board would now be sufficiently 125 clean. But if not clean, after returning the 130

units to their operative position shown in Fig. 1, by turning crank 34 forward, during which return movement of the units droppings will collect against the left-hand side of blades 40, the handle crank is again turned backward and the scrapers will retain said scrapings to drop them through spaces 43 except those which collect against the left-hand side of the left-hand blade. However, 5 these droppings also may be removed by stopping the right hand movement of 18 before it reaches the limit, and then lifting and retaining the left hand scraper clear of the board until this right hand movement is 10 completed. Then return the scraper to its scraping position and it will be leftward of said accumulation of droppings and will retain the same during a subsequent leftward movement of the board until they are scraped 15 into the left hand opening 43. At the conclusion of the cleaning movements of the units they are allowed to remain in their right-hand or operative position shown in Fig. 1. Then the cleaning operation may 20 be completed at a convenient latter time by removing the droppings from holders 44 as 25 above described.

Driving unit 18, during the left-hand cleaning movement moves a distance equal to the 30 length of one of equal units 17 or $a17$ plus the added width of the two spaces 43. Also unit 18 had better be extended beyond the ends of chain 35. So this unit needs to be longer than the other units of the dropping 35 board by the added spaces 43 and a few additional inches. Although the illustrated dimensions of my dropping board are out of normal relation because of the limits of the drawing and but three of these abnormally 40 short sections are shown; yet, from the disclosures above given, it easily may be understood that it is entirely practical to subdivide a dropping board, say, two hundred feet long, into connected units and simultaneously clean them all by an endwise movement of relatively small amount.

When possible, it is preferred that driving 45 unit 18 may enter an adjoining room during the cleaning movement of the board. However, it is practical to have said board move into the open at this time and, when the cleaning is finished, the necessary opening through the end wall to allow said unit to pass may be closed by a door.

50 The scrapers are easily removed from their operative position for special cleaning or the like. In the event that more pressure of the scraper blades on the board is desired heavier bars 37 are used or weights are added thereto.

55 The description has purposely been confined to the particular shapes, materials and related positions of the parts as illustrated, but it is desired that it shall be understood that this disclosure reveals but one set of 60 these elements which coordinate as intended

while I have used many other elements more or less similar with good results. Such and similar variations are also within the purview of this invention.

It is customary to build in dropping boards 70 as a part of the hen-house structure and it may appear that to make them movable would be much more expensive. This is not necessarily true since they may be factory made and thus save expensive hand labor. Furthermore there are other important advantages 75 presented by the unit construction over the fixed type quite aside from the important saving of time required in cleaning among which may be noted their full portability. 80 They may be separately removed from the tracks to be stowed overhead, in a stack in the same or another room or for use in another house, since with proper usage they will serve for a long time. 85

The disclosed means of removing the droppings from the holders may not suit in all cases. If desired to remove them from within the house the holders may be placed horizontally or to slant downward toward their front ends through which their contents may be removed. 90

Having thus disclosed my invention, what I claim as new therein and desire to secure by Letters Patent is,— 95

1. Hen-house, dropping-board cleaning mechanism consisting of a plurality of connected dropping-board units disposed for abutting end to end and also for spacing apart at definite locations, means to connect 100 said units end to end for said abutting and spacing apart, means to mount said units for reciprocal longitudinal horizontal movements, a scraper mounted for vertical movements only at each of said intervening space 105 locations disposed above and across said dropping board to bear on top of the same as it passes beneath, and means to move all of said dropping board units longitudinally in both directions. 110

2. Hen-house, dropping-board cleaning mechanism consisting of a plurality of connected dropping-board units disposed for abutting end to end and also for spacing apart between said ends, means to connect 115 said units end to end for said end abutting and spacing apart, means to mount said units for reciprocal longitudinal horizontal movements adapted to cause said intervening spaces at definite locations, means to move all of said units forward to provide all of said intervening spaces, means to move all of said units backward to close said spaces provided by said forward movements thereof, 120 and a scraper mounted for vertical movements only at each of said intervening space locations and at the rear end of the last of said units when at its said forward location disposed above and across said dropping 125 130

board to bear on the upper surface thereof as it passes beneath.

3. Hen-house, dropping-board cleaning mechanism consisting of a plurality of dropping-board units relatively disposed for abutting end to end and also for spacing apart between said ends, means to mount said units for reciprocal longitudinal horizontal movements adapted to cause said intervening spaces at definite locations when moved in one direction and to close said spaces when moved in the opposite direction, a scraper mounted for vertical movements only disposed above and across said dropping board at each of said intervening space locations and at the rear end of the last of said units when in its said forward location to bear on the upper surface of said dropping board as it passes beneath, and a droppings holder beneath each of said scrapers.

4. A hen-housing dropping board cleaner consisting of a plurality of connected dropping-board units disposed for abutting and also for spacing apart by operative movements thereof, means to mount said units for longitudinal movements, a plurality of spaced scrapers disposed across said dropping-board units to contact with the top surfaces thereof as they pass therebeneath, and means to mount said scrapers for vertical reciprocation.

5. A hen-house dropping board cleaner including a plurality of units, means to connect the units for spacing apart and also for abutting end to end, means to mount said units for longitudinal movements, and a plurality of spaced scrapers disposed across the dropping board units to contact with the top surfaces thereof.

6. Hen-house dropping board cleaning mechanism including a plurality of connected dropping-board units adapted for abutting end to end and also for spacing apart, means to mount said units for reciprocal longitudinal movements, a plurality of spaced scrapers mounted above said board units to contact therewith adapted for movements normal to said board units, and means to move said board units longitudinally in both directions.

NIELS P. NIELSEN.
